UNITED STATES PATENT OFFICE

STEWART SCOTT, JR., OF FERGUSON, MISSOURI

PAPER-FEEDING RACK

Application filed May 16, 1928. Serial No. 278,177.

This invention relates to improvements in paper feeding racks, and consists in the novel construction hereinafter disclosed.

Heretofore, in cutting sheet paper in stacks, the material has been alined on a machine for that purpose and then transported to the table of the cutting machine by truck and loaded from the racks by hand to the cutting table of the cutter. The handling of the paper in this manner tends to cause the sheets to become unaligned on the edges so that it is difficult to feed the paper stacks in the cutting machine.

An object of the present invention is to provide an apparatus whereby the paper in stacks is fed forwardly to the table of the cutting machine mechanically and in such a manner that the steel frames or racks upon which the paper is alined are held in position on the feeding rack and the paper stack moved forwardly uniformly, thereby preventing the edges of the sheets composing the stack from becoming unaligned.

Additional objects of the construction will be apparent from the following description thereof taken in connection with the accompanying drawings in which

Fig. 1 is a plan view.

Fig. 2 is a side elevation.

Fig. 3 is a front view.

Fig. 4 is a side elevation of the paper stack supported on the frame.

Fig. 5 is a detail view of the frame structure.

Fig. 6 is a cross section showing the formation of the frame bar and taken substantially on the line 6—6 of Fig. 5.

In the embodiment of the invention illustrated in the drawings the feeding rack is shown as including a rectangular frame having a base member 1, upright supports 2 and top members 3 and 4. The frame is preferably mounted on rollers 5 so that it may be readily moved from the point of loading to alignment with the forward edge of the feeding table of the cutting machine.

It will be noted from the drawings that the members 3 and 4 form an open frame, with the members 4 in a plane above the members 3. At each end of the members 3 are

brackets 6 upon which are supported rear shaft bearings 7 and front shaft bearings 8. Transversely of the rear end of the rack a shaft 9, upon which are mounted a plurality of pulleys 10 in transverse spaced relationship, is journalled in said bearings 7. Transversely of the front end of the rack a shaft 11 is journalled in the bearings 8 and a plurality of pulleys 12 are mounted on said shaft 11 in transverse spaced relationship and opposite the pulleys 10. Continuous belts 13 are mounted over the pulleys 10 and 12, the upper face of said belts extending in a plane above the upper face of the members 4.

The shaft 11 is provided with a power pulley 14 which is driven from any suitable source of power, either by a belt connection 15 or by direct drive. By driving the shaft 11 it is obvious that the belts 13 will move forwardly uniformly from the rear to the front end of the rack.

The stack of sheet paper 16 is alined on metal frames rectangular in form and comprising transverse end members 17 and spaced longitudinal members 18. The members 18 are connected to the members 17 and are spaced so that said members 18 lie in the interval between the belts 13 and along the outer edge of the outer belts.

The frame is preferably constructed as shown in the drawings, namely, by forming it from the end members 17 in the form of angle bars with the longitudinal members 18 in the form of channel bars, said members 18 being respectively attached to the under faces of the top walls of the members 17 and removably secured thereto by screws 19, as illustrated in detail in Fig. 6. This provides a readily portable frame for the paper stack, the ends of the stack resting within the members 17 and supported by the upper faces of the members 18.

The members 4 support blocks 20 that form rests for the frame when the frame for supporting the stack of paper is placed on said block. The top faces of the blocks 20 lie slightly below the upper plane of the belts 13 so that the paper stack, while supported by the frame, may be lifted in place over the belts and the frame will move below the plane

of the belts and rest on the supporting blocks 20. This brings the belt faces in contact with the lower sheet of the stack so that, when the shaft 11 is operated, the entire stack will 5 be moved forwardly from the frame and onto the cutting table of the cutter.

While the apparatus has been described as particularly applicable for the handling of paper stacks for feeding the same to the table 10 of a cutting machine, the same construction obviously can be used for handling paper for any general purpose where it is desired to remove the stack of paper intact and in alinement onto a flat surface.

15 The construction of the present invention has very greatly facilitated the handling of large stacks of paper which are ordinarily handled in reams having considerable bulk and great weight. By the use of the rack the 20 handling time has been very greatly reduced and furthermore the condition of the stack is maintained in perfect alinement. The weight of the stack is sufficient to cause a frictional contact with the belts and to maintain 25 the surface contact between the separate sheets. It is useful for handling all classes of paper and is particularly useful in handling paper where the sheets are first printed and then alined and are required to be cut accurately for labels and the like. It has been 30 found to be specially useful in handling calendered or glazed paper, the sheets of which, when manually handled, tend readily to get out of alinement. By the use of the machine 35 with greatly reduced labor very heavy stacks may be handled, as it is essential to engage the stack by the hands of the operator until the same is fully positioned on the cutting table or other horizontal support, as the stack 40 may be placed upon the feeding rack by handling the supporting frame and the belts advance the stack intact and in alinement to the horizontal surfaces. It can be readily 45 handled by the operator in the usual manner.

50 I am aware that the invention may be modified in various particulars without departure from the nature and principle thereof. I do not restrict myself unessentially, but what I claim and desire to secure by Letters Patent is:

55 1. An apparatus of the class described comprising a main frame, and a plurality of spaced belts supported in the top of said frame, in combination with a portable supporting frame for a stack of paper comprising spaced longitudinal members arranged to seat between said belts and to be retained by the main frame below the surface of the belts, and means for moving said belts in unison 60 whereby said stack of paper is moved forwardly in alinement.

65 2. An apparatus of the class described comprising a portable main frame, and a plurality of spaced belts supported in the top of said frame, in combination with a portable

70 unattached supporting frame for a stack of paper comprising spaced longitudinal members arranged to seat between said belts and to be retained by the main frame below the surface of the belts, and means for moving said belts in unison whereby said stack of paper is moved forwardly in alinement.

75 3. A paper feeding rack comprising a main frame, shafts supported at each end of said frame in parallel alinement, a plurality of spaced pulleys carried by said shafts, said pulleys being alined in longitudinal pairs, endless belts extending over said pulleys, means for driving one of said shafts, and a portable frame separable from said main frame and mountable thereon for positioning a stack of paper on the upper sides of 80 said belts.

85 4. A paper feeding rack comprising a main frame, shafts supported at each end of said frame in parallel alinement, a plurality of spaced pulleys carried by said shafts, said pulleys being alined in longitudinal pairs, endless belts extending over said pulleys, means for driving one of said shafts, and means for positioning a stack of paper on the upper surface of said belts comprising an open portable frame having end members and longitudinally extending spaced intermediate members, said intermediate members being adapted to seat on the main frame below the upper face of the belts whereby the belts frictionally engage the under face of the stack.

90 5. In an apparatus of the class described, the combination with a main frame, of a plurality of friction belts arranged transversely of the frame, means for driving said belts forwardly in unison, and means for positioning a stack of paper on said belts comprising an open portable frame adapted to be positioned on the main frame with the members of the frame out of contact with the belts whereby the stack is engaged and moved forwardly by the belts, and means for supporting frame on the main frame below the surface of the belts.

95 6. In an apparatus of the class described, the combination with a main frame, and wheels on said main frame, of a plurality of friction belts arranged transversely of the frame, means for driving said belts forwardly in unison, and means separable from said main frame and mountable thereon for positioning a stack of paper on said belts comprising an open frame adapted to be positioned on the main frame with the members of the frame out of contact with the belts whereby the stack is engaged and moved forwardly by the belts and the supporting frame on the main frame.

100 7. An apparatus of the character described comprising a main frame, and a plurality of spaced belts operatively supported in the top of the frame, in combination with a port-

able supporting frame separable from said main frame and mountable on said main frame for depositing on said belts a stack of paper, and means in said main frame for supporting said portable frame below the stack of paper deposited on said belts by said portable frame.

8. In an apparatus of the character described the combination with a main frame, parallel rotary shafts supported by said frame, pulleys mounted on said shafts for rotation thereby, endless friction belts mounted on and operated by said pulleys, and a portable frame for carrying a stack of paper and being mountable on said main frame below the upper sides of said belts and having openings for receiving said belts to permit the deposit on said belts of the paper on said portable frame.
